UNITED STATES PATENT OFFICE.

ERNEST L. SONS, OF PITTSBURGH, PENNSYLVANIA, ASSIGNOR OF ONE-HALF TO
WILLIAM L. McCANDLESS AND ONE-FOURTH TO SAMUEL A. BOYD, BOTH OF
PITTSBURGH, PENNSYLVANIA.

LIFE-SAVING DEVICE.

1,224,679.

Specification of Letters Patent.

Patented May 1, 1917.

Application filed August 9, 1916. Serial No. 113,868.

To all whom it may concern:

Be it known that I, ERNEST L. SONS, a citizen of the United States of America, residing at Pittsburgh, county of Allegheny 5 and State of Pennsylvania, have invented certain new and useful Improvements in Life-Saving Devices, of which the following is a specification.

This invention relates to a life saving 10 device, and has for its object to provide a marine vessel, in a manner as hereinafter set forth, with a detachable compartment superstructure for the housing of the passengers and crew of a ship, when the latter 15 is damaged and there is a possibility of its sinking, and the providing of said superstructure with buoyant elements to prevent it from submerging when detached from the ship and floating away.

20 A further object of the invention is to provide a detachable compartment buoyant superstructure for ships for the purpose set forth and having a wireless telegraph apparatus permitting of the calling for assistance when the superstructure is detached from the ship and floating away therefrom.

25 A further object of the invention is to provide a device for the purpose set forth which is comparatively simple in its construction and arrangement, which can be used for passengers or members of the crew 30 of a ship when it is not detached therefrom, strong, having means to prevent any possibility of submergence, readily connected 35 to and detached from the deck of a vessel, and inexpensive to manufacture.

With the foregoing and other objects in view the invention consists of the novel construction, combination and arrangement 40 of parts as hereinafter more specifically described and illustrated in the accompanying drawings, wherein is shown an embodiment of the invention, but it is to be understood that changes, variations and modifications 45 can be resorted to which come within the scope of the claims hereunto appended.

In the drawings wherein like reference characters denote corresponding parts throughout the several views:—

50 Figure 1 is a diametrical view illustrating a hull of a vessel provided with a superstructure in accordance with this invention.

Fig. 2 is a longitudinal sectional view of the superstructure, in accordance with this

invention, and which provides a life saving 55 device.

Fig. 3 is a cross sectional view of one of the buoyant members.

Referring to the drawings in detail 1 denotes the hull of a vessel and which has detachably connected with the upper deck thereof a superstructure or housing boat, in accordance with this invention, which provides a life saving device for the passengers and crew of the vessel when occasion 60 65 so requires.

Preferably the superstructure is rectangular in contour and consists of an outer rectangular frame 2 and a series of inner rectangular frames 3, 4, 5, and 6 which are 70 spaced from each other and from the outer frame 2. The frames 3 and 4 are arranged in parallelism and a like arrangement is had in connection with the frames 5 and 6. The frames 3 and 4 are arranged above the frames 75 5 and 6. Arranged in the space between the tops of the frames 3 and 4 and the top of the frame 2 is a series of longitudinally extending rows of buoyant elements 7. Positioned in the space formed between the bottoms of the frames 3, 4, and the tops of the frames 5, and 6, is a series of longitudinally extending rows of buoyant elements 8. Arranged in the space formed 80 between the bottoms of the frames 5 and 6 85 and the bottom of the frame 2 is a series of longitudinally extending rows of buoyant elements 9. Arranged in the space formed by the opposing ends of the frames 3, 4, 5, and 6 is a series of vertical rows of buoyant 90 elements 10. Positioned between the outer ends of the frames 3, 6 and one end of the frame 2 is a series of vertical rows of buoyant elements and arranged between the other end of the frame 2 and the outer ends 95 of the frames 4 and 5 is a series of vertical rows of buoyant elements 12.

The buoyant elements of the rows 7, 8, 9, extend longitudinally and the buoyant elements of the rows 10, 11 and 12 extend 100 vertically. The buoyant elements of the rows constitute sustaining members.

Only one longitudinal row 7, 8, and 9 and only one vertical row 10, 11 and 12 of buoyant elements is illustrated.

Associating with each of the rows 7, 8 and 9 of the buoyant elements is an air supply pipe 13 and associating with each of the

rows 11 and 12 is an air supply pipe 14 and the said pipes 14 are coupled with the pipes 13. Associating with each of the rows 10 of buoyant elements is a vertically disposed 5 air pipe 15 and which communicates at the lower end thereof with the air supply pipes 13 which are arranged between the bottoms of the frames 5, 6, and the bottom of the frame 2. Communicating with one of the 10 pipes 13, and arranged at the bottom of the superstructure, is an air feed pipe 16 which leads from a compressor 17.

Each of the buoyant elements is cylindrical in contour and consists of an inflatable 15 inner tube 18, which is inclosed by a thin metallic cylinder 19 for protecting the tube 18. The tube 18 is inset as at 20 to provide a pocket 21, through which extends an air supply pipe 13, or 14, or 15. Leading from 20 the air supply pipe to each sustaining element of the rows is a check-valve 22 of known construction.

Any suitable means can be employed between the frames to prevent shifting of the 25 sustaining members, but the valve connection between them and the air supply pipe is in most instances all that is necessary.

The superstructure is mounted upon the upper deck and detachably connected there- 30 with by hinged arms 23, connected with the sides of the superstructure as at 24, and detachably connected at their lower ends by hooks 25.

The superstructure is provided with a 35 wireless telegraph device, as indicated conventionally at 26. The superstructure also has windows 27 and entrance doors 28.

When the vessel should become damaged and in danger of sinking the superstructure 40 is detached from the deck and as the vessel sinks, will float off, or the same can be dislodged from the hull prior to the sinking of the vessel and the sustaining elements will prevent the superstructure from submerging.

45 What I claim is:—

1. A device for the purpose set forth comprising a compartment superstructure, inflatable sustaining elements interposed between the floors and walls of the compartments of said super-structure, protecting cylinders inclosing each of said inflatable elements, and means for inflating said elements.

2. A device for the purpose set forth comprising a compartment super-structure, inflatable sustaining elements interposed between the floors and walls of the compartments of said super-structure, protecting

cylinders inclosing each of said inflatable elements, and means for inflating said elements, a wireless telegraph apparatus carried by said super-structure. 60

3. A device for the purpose set forth comprising a compartment super-structure, inflatable sustaining elements interposed be- 65 tween the floors and walls of the compartments of said super-structure, protecting cylinders inclosing each of said inflatable elements, and means for inflating said elements, and means for detachably connecting 70 said super-structure upon the deck of a vessel.

4. A device for the purpose set forth comprising a compartment super-structure, inflatable sustaining elements interposed be- 75 tween the floors and walls of the compartments of said super-structure, protecting cylinders inclosing each of said inflatable elements, and means for inflating said elements, a wireless telegraph apparatus carried by the said super-structure, and means for detachably connecting said super-structure 80 upon the deck of a vessel.

5. A device for the purpose set forth comprising a compartment super-structure, inflatable sustaining elements interposed be- 85 tween the floors and walls of the compartments of said super-structure, protecting cylinders inclosing each of said inflated elements, said sustaining elements arranged in 90 longitudinal and vertical rows, and an independent air supply pipe for the elements of each row, an inlet valve connection between each pipe and its associated element, and means for feeding air to said pipes. 95

6. A device for the purpose set forth comprising a compartment super-structure, inflatable sustaining elements interposed be- 100 tween the floors and walls of the compartments of said super-structure, protecting cylinders inclosing each of said inflated elements, said sustaining elements arranged in longitudinal and vertical rows, and an independent air supply pipe for the elements of each row, and inlet valve connection be- 105 tween each pipe and its associated element, and means for feeding air to said pipes, and a wireless telegraphic apparatus carried by said super-structure.

In testimony whereof I affix my signature in the presence of two witnesses. 110
